UNITED STATES PATENT OFFICE.

JOHN P. RYAN, OF WORCESTER, MASSACHUSETTS.

HYDRAULIC APPARATUS.

1,268,884.

Specification of Letters Patent. Patented June 11, 1918.

Application filed June 14, 1917. Serial No. 174,707.

To all whom it may concern:

Be it known that I, JOHN P. RYAN, a citizen of the United States, residing at Worcester, in the county of Worcester and 5 State of Massachusetts, have invented a new and useful Hydraulic Apparatus, of which the following is a specification.

This invention relates to a hydraulic apparatus, and particularly to means for manually actuating a hydraulic motor.

It is the general object of my invention to provide hydraulic apparatus by the operation of which continuous rotary motion of a driving shaft may be effectively obtained 15 by manual reciprocation of a rocking lever or other similar mechanism.

With this general object in view, one feature of my invention relates to the provision of a plurality of hydraulic cylinders each 20 having a piston connected to a rocking lever or other actuating device, in combination with a rotary hydraulic motor connected for operation from said cylinders. A further feature of my invention relates to 25 the provision of connections from said cylinders to and from said motor so disposed that water forced from one cylinder or set of cylinders to said motor will be returned to the second cylinder or set of cylinders 30 for further use.

Further features of my invention relate to arrangements and combinations of parts hereinafter described and more specifically pointed out in the appended claims.

35 A preferred form of my invention is shown in the drawings, in which

Figure 1 is a front elevation, partly in section, of my improved hydraulic apparatus, and

40 Fig. 2 is a detail plan view of the actuating mechanism.

Referring to the drawings, my hydraulic apparatus comprises two separate structures 10 and 11 suitably mounted upon a frame 45 12. Each of the structures 10 and 11 is composed of one or more hydraulic cylinders 13 or 13^a, each connected by a short pipe 14 to stand pipes 15 or 15^a and by a second short pipe 16 to stand pipes 17 or 17^a.

50 Piston rods 18 and 19 extend vertically through the structures 10 and 11 and actuate pistons 20 in each cylinder 13 or 13^a. The pipes 14 and 16 connect with each cylinder

near the bottom thereof and below the lower limit of travel of the piston 20 therein.

The piston rods 18 and 19 are connected by links 21 to the opposite ends of a rocking lever 22 fixed to a shaft 23 mounted in bearings 24 secured to the frame 12. The shaft 23 may be actuated to reciprocate the 60 piston rods in any convenient manner as by means of a pedal lever 25 (Fig. 2).

A hydraulic motor having a casing 30 is rigidly supported upon the structures 10 and 11, the wheel 31 of said motor being 65 mounted upon a shaft 32 from which power may be taken for any desired purpose. The stand pipes 15 and 15^a are connected to the upper part of the casing 30 by horizontal pipes 33 and 34, said pipes being provided 70 with check valves 35 and 36 respectively which open toward the motor. The motor casing is also connected by a branched passage 37 to the stand pipes 17 and 17^a, and check valves 38 and 39 are provided in the 75 branches of said passage 37, said valves opening away from the casing 30.

Having described the construction of my improved apparatus, I will now describe its operation. Let it be assumed that the parts 80 are in the position shown in Fig. 1 and that the piston rod 18 is moved downward through the operation of the pedal lever 25. As the rod 18 with its pistons 20 moves downward the water contained in the cylinders 13 of the structure 10 is forced through 85 the pipes 14 to the stand pipe 15 from which it flows to the pipe 33 and past the check valve 35 to the casing 30 and wheel 31. The check valve 36 is closed, preventing any of 90 the water from flowing through the pipe 34 to the opposite stand pipe 15^a and connections 14.

The water is thus forced downward past the motor wheel 31 to the branched passage 95 37. The check valve 38 will be closed by the pressure upon its rear side from the cylinders 13 in the structure 10, and at the same time the pressure upon the check valve 39 will be relieved by the upward movement of 100 the pistons 20 carried by the piston rod 19. The water flowing through the casing 30 will thus pass into the right-hand stand pipe 17^a and through the short pipes 16 into the cylinders 13^a of the structure 11, in which 105 the pistons are rising.

This operation will continue until the pistons 20 in the structure 10 reach their lowest point, at which time the motion of the pedal lever 25 and rocking lever 22 will be manually reversed. The operation will then be repeated with the water flowing from the cylinders 13^a in the structure 11 to the stand pipe 15^a, the pipe 34 and past the check valve 36 to the motor casing 30, thence through 36 to the passage 37, past the check valve 38, and through the left-hand stand pipe 17 and short pipes 16 to the cylinders 13 in the structure 10.

Suitable vent holes 40 will be provided 15 above the pistons 20 in each cylinder to prevent the formation of a vacuum as the pistons descend.

The reciprocating motion of the shaft 23 and lever 22 is thus changed by the hydraulic apparatus to a continuous rotary motion 20 of the driving shaft 32. It will be noted that the transformation of the motion is caused by the interchange of water between the cylinders and that the mechanical moving parts are few in number and of the simplest construction.

Having thus described my invention, it will be evident that changes and modifications can be made therein by those skilled 30 in the art without departing from the spirit and scope of my invention as set forth in

the claims, and I do not wish to be otherwise limited to the details herein disclosed, but what I claim is—

1. A hydraulic apparatus comprising two structures each composed of a plurality of cylinders, a piston rod for each structure having a piston in each cylinder thereof, means to actuate said rods simultaneously in opposite directions, a hydraulic motor, and connections between said cylinders and said motor whereby water forced from one series of cylinders flows past said motor to the opposite series of cylinders, thereby actuating said motor. 45

2. A hydraulic apparatus comprising two structures each composed of a plurality of cylinders, a piston rod for each structure having a piston in each cylinder thereof, means to actuate said rods simultaneously in opposite directions, a hydraulic motor, separate pipes leading from each set of cylinders to said motor, check valves in said pipes permitting flow toward said motor only, additional pipes from said motor to each set of 55 cylinders, and check valves in said additional pipes permitting flow toward said cylinders only.

In testimony whereof I have hereunto affixed my signature.

JOHN P. RYAN.
